UNITED STATES PATENT OFFICE.

CHARLES W. HART, OF TROY, NEW YORK, ASSIGNOR TO HARRIET A. HART,
OF SAME PLACE.

DESIGN FOR A FULCRUM-POST FOR MOPS.

SPECIFICATION forming part of Design No. 22,812, dated September 26, 1893.

Application filed July 26, 1893. Serial No. 481,574. Term of patent 14 years.

To all whom it may concern:

Be it known that I, CHARLES W. HART, a citizen of the United States, residing at Troy, county of Rensselaer, and State of New York, have invented and produced a new and original Design for a Fulcrum-Post for Mops, of which the following is a specification, reference being had to the accompanying drawing, which represents in a single figure a side 10 elevation of a fulcrum-post embodying my design.

The post comprises a lower attaching portion having bifurcate arms A—, A—, and a shank projecting upwardly from the bifurcate arms and terminating in a head having an eye or aperture formed by a fork in the upper extremity of the shank and a cross-bar connecting the branches of the fork near their ends. A pointed spur projects down-

wardly between the bifurcate arms, A—, A—, 20 in line with the upwardly projecting shank.

The leading feature of my design consists of the pointed spurs C—, C—, projecting interiorly from the outer ends of the diverging bifurcate arms A—, A—, which arms have 25 curved inner surfaces B—, B—, near their junction, the curves B—, B—, together forming an approximate semicircle.

What I claim as new, and desire to secure by Letters Patent, is— 30

The design for a fulcrum-post for mops, herein shown and described.

In testimony whereof I have hereunto set my hand this 20th day of July, 1893.

CHARLES W. HART.
